UNITED STATES PATENT OFFICE.

HARVEY LESLIE GREGWARE, OF BEVERLY, MASSACHUSETTS, ASSIGNOR TO FRED M. PAGE, OF LYNNFIELD, MASSACHUSETTS.

TAPE-MOISTENING MACHINE.

1,352,892.

Specification of Letters Patent. Patented Sept. 14, 1920.

Application filed March 24, 1920. Serial No. 368,228.

To all whom it may concern:

Be it known that I, HARVEY L. GREGWARE, a citizen of the United States, residing at Beverly, in the county of Essex and State of 5 Massachusetts, have invented certain new and useful Improvements in Tape-Moistening Machines; and I do hereby declare the following to be a full, clear, and exact description of the invention, such as will enable 10 others skilled in the art to which it appertains to make and use the same.

This invention relates to a tape moistening machine.

The object of the invention is to re-organize and improve the construction of tape moistening machines to render them more efficient, practical and better adapted to accomplish the purposes for which they are designed.

20 With this object in view the invention consists in the tape moistening machine herein-after described and claimed.

In the drawings, Figure 1 illustrates the tape moistening machine in side elevation; 25 Fig. 2 is an enlarged detail view showing the tape severing and holding device; Fig. 3 is a vertical section on the line 3—3 of Fig. 2; and Figs. 4 and 5 are details to be referred to.

A tape moistening machine embodying the 30 present invention comprises, in general, a relatively heavy base portion, a moistening device at one end of the base portion, a device mounted on the base for rotatably supporting a roll of tape, a cover hinged to the 35 rear of the base capable of completely covering the roll of tape, and a device mounted on the base between the moistening roll and the roll of tape for severing the tape when the free end thereof is manually moved in an 40 upward direction and for firmly clamping the tape during the severing operation.

The illustrated embodiment of the invention is described as follows: The base 10 is cast in the form illustrated in Fig. 1 with 45 side walls 12 at one end portion thereof. The side walls 12 are connected by a transverse wall 14 forming a three walled receptacle in which is removably received a trough 16. The trough 16 is formed of sheet metal 50 and is provided with ears 18 extended over the tops of the side walls 12 to retain the trough in a substantial stationary position within the receptacle. A moistening roll 20 is journaled in open V-shaped grooves 22 in 55 the top of the sides 12 so that both the roll 20 and the trough 16 may be readily removed.

The base 10 is provided at near its center with a roll support 25 for a roll of tape 26. A small pin 28 is extended through the center of the roll of tape and the end portions 60 thereof are loosely supported in slots 29 in uprights 30 of the support 25. The support 25 is formed of a single strip of resilient steel bent into substantially U-shape and secured to the base 10 by screws 32. The resiliency 65 of the uprights 30 is such that they may be readily spread apart to permit the roll of tape to be inserted therebetween and is also such as to offer a slight frictional resistance to the rotation of the roll of tape. A sheet 70 metal cover 36 is pivotally mounted on the rear of the base 10 upon a pintle 37 supported in small lugs 40 extended upwardly from the rear of the base. The cover 36 serves to completely cover the roll of tape to conceal 75 it from view and also to retain the pin 28 in an operative position and to prevent its withdrawal from the slots 29.

Provision is made for severing the tape and for firmly clamping it during the severing operation so that the latter may be performed efficiently and without unwinding additional tape from the roll. To these ends a tape severing and clamping device is mounted upon the base 10 between the moistening roll 20 and the roll of tape 26. The tape severing and clamping device comprises 80 a clamp; a movable knife and a toggle connection between the knife and clamp whereby the strain upon the knife during the severing operation is increased by and transmitted 85 through the toggle connection to the clamp so that the tape is securely held by the clamp during the severing operation. The clamp comprises a wire 70 which cooperates with an 90 elongated slot 72 in an abutment 74 formed by the angled upper end of a bracket 76. The bracket 76 is riveted to a vertical supporting plate 78. The vertical supporting plate 78 is provided with a transverse slot 100 80 through which the tape passes from the roll 26 over the abutment 74 and beneath the wire 70. A plate spring 82 is interposed between the wire 70 and an upper abutment 84 formed by the angled lower end of a second 105 bracket 86 riveted to the upper portion of the supporting plate 78. The opposite ends of the wire 70 are extended upwardly and form connectors 88, the upper out-turned ends of which, extending outwardly through the 110 elongated clearance slots in the ears 96 of the bracket 86, are pivoted in holes in ears

90 extended from a knife 92. The knife 92 is pivoted upon a pintle 94, the opposite ends of which are carried by the ears 96 of the bracket 86. The knife 92 and connectors 88 5 form a toggle, clearly illustrated in Fig. 2, by which the wire 70 is depressed when upward strain is placed upon the cutting edge of the knife during the operation of severing the tape.

10 The machine is prepared for use by supplying the trough 16 with water and inserting a roll of tape between the uprights 30, after which the end of the tape is passed through the clamp. For this purpose the 15 knife 92 is depressed into the dotted position illustrated in Fig. 1, thereby raising the wire 70 away from the abutment 74 so that the end of the tape may be freely passed through the slot 80 and beneath the wire 70.

20 In the use of the machine, the end of the tape is drawn downwardly over the moistening roll and the drag exerted thereon by the wire 70 operates to cause the tape to hug the moistening roll so as to be efficiently moistened.

30 After the desired length of tape has been moistened, the free end is moved upward, thereby drawing the tape against the knife. The pressure of the tape against the knife turns it in its bearings and thereby causes the wire 70 to clamp the tape firmly in a tortuous position between the wire and the sides of the elongated slot, thereby holding it from paying off; as the pull upon the tape 35 is continued, it is severed by the pressure which it exerts upon the knife.

40 A feature of the invention which contributes to the efficient operation of the machine, resides in the construction of the clamp, whereby the tape is clamped in a tortuous position during the severing operation, as is shown in detail in Fig. 5.

Having thus described the invention what is claimed is:—

45 1. A tape moistening machine having, in combination, a base, a roll support mounted thereon, a moistener mounted on the base, means for severing the tape between the moistener and roll support, and a clamping device through which the tape passes adapted 50 upon the initiation of the severing operation to depress the tape into a tortuous position and to clamp it in such position during the severing operation.

55 2. A tape moistening machine having, in combination, a base, means for rotatably supporting a roll of tape on the base, a moistener at one end of the base, and a tape severing and clamping device mounted on the 60 base intermediate the moistener and roll, for severing the tape and clamping it in a tortuous position by the pressure exerted by the knife during the severing operation.

65 3. A tape moistening machine having, in combination, a base, a roll support compris-

ing a pair of uprights mounted on the base, a moistener, a movable knife, a clamp through which the tape passes as it is drawn from the roll over the moistener, and connections between the knife and the clamp 70 whereby the tape is clamped in a tortuous position by the pressure exerted upon the knife during the severing operation.

4. A tape moistening machine having, in combination, a base, a roll support, a moistener, a movable knife, a horizontal clamp beneath which the tape passes, an abutment provided with a slot therein, a spring for yieldingly holding the clamp and tape against the abutment to frictionally resist its 80 movement thereover, and connections between the clamp and the knife whereby during the severing operation the clamp is moved into the slot and co-operates with the sides thereof to clamp the tape in a tortuous 85 position.

5. A tape moistening machine having, in combination, a base, a roll support, a moistener, a supporting plate extended vertically from the base intermediate the moistener and roll support having a slot therein through which the tape passes from the roll to the moistener, a clamp mounted on the plate and adapted to frictionally resist movement of the tape, a knife pivoted upon 95 the plate above the clamp, and connections between the knife and clamp whereby the tape is clamped during the severing operation.

6. A tape moistening machine having, in combination, a base, a roll support, a moistener, a pivoted knife and a clamp, said clamp comprising an abutment having a slot therein, a movable clamp, a spring for yieldingly holding the clamp against the abutment, and connections between the clamp and knife whereby the tape is clamped in a tortuous position between the clamp and the sides of the slot during the severing operation, and for moving the clamp away from 110 the abutment to permit the end of the tape to be passed therebetween when the knife is depressed.

7. A tape moistening machine having, in combination, a base, a roll support mounted 115 thereon, a moistener, a knife, a clamp, and a toggle connection between the knife and clamp by which the strain upon the knife during the severing operation is transmitted to the clamp and operates to clamp the tape 120 securely.

8. A tape moistening machine having, in combination, a base, a moistener, a roll support, a knife, and a toggle-operated clamp connected with the knife so that cutting 125 pressure of the tape on the knife operates the clamp to clamp and hold the tape from paying off during the severing operation.
